A. B. CAMERON.
ORNAMENTAL PANEL.

No. 19,474.

Patented Dec. 10, 1889.

UNITED STATES PATENT OFFICE.

ALLAN B. CAMERON, OF WILLIAMSPORT, PENNSYLVANIA.

DESIGN FOR AN ORNAMENTAL PANEL.

SPECIFICATION forming part of Design No. 19,474, dated December 10, 1889.

Application filed November 12, 1889. Serial No. 330,075. Term of patent 14 years.

To all whom it may concern:

Be it known that I, ALLAN B. CAMERON, of Williamsport, Lycoming county, Pennsylvania, have invented and produced a new and original Design for Panels, of which the following is a specification, reference being had to the accompanying photograph, forming part hereof.

My design relates to an ornamental panel having on its surface the configuration hereinafter set forth.

My design consists of the raised regular diamonds A and B in juxtaposition. Between the diamonds A and B appear the raised diamonds D and E. Upon the surfaces of the diamonds D E appear grooves or channels, as F, which extend from the meeting-point G of

said diamonds outward to the edges of said diamonds D E. On each side of the diamonds D and E appear groups of diamonds, 20 as G H I J K L, each group consisting of a number of small diamonds symmetrically disposed and arranged, as represented in the photograph. The general effect produced is as if the grooves meeting on contiguous diamonds 25 D D' had been extended so as to intersect.

I claim—

The design for an ornamental panel, substantially as herein shown and described.

ALLAN B. CAMERON.
